UNITED STATES PATENT OFFICE.

ARMAND GODEFROID, OF AIX-LA-CHAPELLE, GERMANY.

CASH-REGISTER.

SPECIFICATION forming part of Letters Patent No. 733,476, dated July 14, 1903.

Application filed November 27, 1901. Serial No. 83,947. (No model.)

To all whom it may concern:

Be it known that I, ARMAND GODEFROID, merchant, a subject of the German Emperor, residing at 42 Bergdrisch, in the city of Aix-la-Chapelle, in the Kingdom of Prussia, German Empire, have invented a certain new and useful Cash-Register, of which the following is a specification.

This invention has reference to a cash-
register, and it is so arranged and constructed
that an endless feeding ribbon, which is di-
vided into sections by a series of projecting
transverse ribs, is fed forward for the dis-
tance of one section during the first part of
the downward movement of an operating-
handle actuated from the outside of the ap-
paratus, the said handle being linked to a
shaft on which a cam is mounted and which
operates a ratchet-gear arranged upon one
roller of the endless feeding ribbon or carrier
by the medium of levers actuated by said
cam, while during the subsequent part of the
downward movement of said operating-han-
dle the plate or chute through which the coin
is inserted into the apparatus is turned, caus-
ing the coin to drop upon the endless ribbon-
like carrier and between two succeeding
transverse ribs, the said chute or entering-
plate being brought back into its original po-
sition by the upward movement of the said
operating-handle, whereby the pawl of the
ratchet-gear is at the same time made to en-
gage with the next tooth of the said gearing.

By the arrangement of parts as above out-
lined the several operating periods of the ap-
paratus are sharply defined from each other,
and the possibility of controlling especially
the last payments is greatly increased.

On the accompanying drawings, represent-
ing an embodiment of my invention, Figure
1 is a longitudinal section. Fig. 2 is a plan
view of a cash-register, with parts in section.

Fig. 3 is a detail of the ratchet-gearing.

In the drawings, *a* is a casing, in which is suit-
ably mounted the endless carrier *d* upon the
guide-rollers *b c*, the said carrier being pro-
vided with projecting ribs *e* transverse to the
direction of movement of the same and at a
certain distance from each other, which in the
present instance is equal to a quarter of the
periphery of the roller *c*. In order to pre-
vent slipping of the endless carrier upon the

rollers *b c*, the carrier is provided with en-
larged portions *f*, which are adapted to en-
gage with the teeth *g* of the rollers *b c*. 55

The handle *i* is rotatably journaled in the
front wall *h* of the casing *a* and is linked to
the shaft *m* by means of the link *k* and the
arm *l*, pivoted thereto. Upon the shaft *m* is
mounted a cam-disk *n*, which upon the de-
scent of the handle *i* raises the lever *o*, rota-
bly journaled in the side wall *a*. The slot-
ted end of the said lever *o* engages the pin *p*
of a plate *r*, which is free to oscillate around
the shaft *q* of the roller *c*, and the said plate 65
r is thereby raised, which also causes the
raising of the spring-acting pawl *s*, connected
therewith, and the turning of the ratchet
gear-wheel *t* for a quarter of a revolution, the
said ratchet-wheel being rigidly connected 70
to the roller *c*. The endless carrier *d* is thus
fed forward for the distance of one section
between two succeeding transverse ribs.
While the roller *c* is turned for a quarter of
a revolution, the handle *i* has completed about 75
half its downward movement, and then only
the receiving-plate *u* is being inclined, so as
to allow the coin resting thereon to slide upon
the endless carrier, the movement of which
has now stopped. Thence the coin drops into 80
the receptacle *2*. The inclination of the plate
u is caused by the small cam-disk *v*, which is
also mounted upon the shaft *m* and which is
arranged to strike against the lever *w*, rota-
bly journaled in the front wall *h* of the cas- 85
ing *a*, and which by means of the rod *x* in-
clines the plate or chute *u*. As soon as the
handle *i* has reached the lowest point of its
downward movement the pulling-spring *y*
serves to restore it to its initial position, 90
while the backward movement of the endless
carrier *d* is prevented by the ratchet-gearing *z*.

What I claim, and desire to secure by Let-
ters Patent of the United States, is—

A cash-register comprising the combination 95
with a rotatable entrance or receiving plate
for the coin of an endless carrier and trans-
verse ribs on said carrier at certain distances
from each other, gearing and an operating-
lever actuated from the outside of the appa-
ratus for controlling the movement of the said
carrier, cams journaled to the casing and
linked to the said operating-handle and spring
connection between the said cams and the 100

said entrance-plate whereby during part of the downward movement of the said operating-handle the endless carrier is fed forward for the distance of one section, while during 5 the rest of the downward movement of the said operating lever or handle the said entrance or receiving plate for the coin is inclined, and by means of its spring connection the said entrance or receiving plate returns

to its initial position during the upward movement of the operating lever or handle.

In witness whereof I have hereunto set my hand in presence of two witnesses.

ARMAND GODEFROID.
